E. N. ELLIS.
 COMBINED CURTAIN AND PORTIERE HANGER.
 APPLICATION FILED APR. 13, 1920.
1,436,702. Patented Nov. 28, 1922.

UNITED STATES PATENT OFFICE.

EVELYN N. ELLIS, OF ADEBOLT, IOWA.

COMBINED CURTAIN AND PORTIÈRE HANGER.

Application filed April 13, 1920. Serial No. 373,603.

To all whom it may concern:

Be it known that I, EVELYN N. ELLIS, a citizen of the United States, residing at Adebolt, in the county of Sac and State of Iowa, have invented certain new and useful Improvements in Combined Curtain and Portière Hangers, of which the following is a specification.

The present invention relates to improvements in a combined curtain and portière hanger and more particularly relates to an improved device for hanging portières and curtains in connection with windows, doors, stages, et cetera.

An object of the invention is to provide an improved curtain and portière hanger for holding the portières so that they may be removed for purposes of cleaning and may be interchanged with facility.

A further object of the present invention resides in providing an improved mechanism whereby the curtain may be opened and closed from a point below and at one side.

With the foregoing and other objects in view the invention consists in the constructions, combinations and arrangements of parts as hereinafter described and more particularly pointed out in the claim.

Referring to the drawings, wherein like numerals denote like or corresponding parts throughout the several views,

Fig. 1 is a view in elevation, with the lower portion broken away of a window or stage casing having the improved portière and curtain hanger applied thereto.

Fig. 2 is a view in elevation of one of the brackets.

Fig. 3 is an end view of the same.

Fig. 4 is a view in elevation of the other bracket.

Fig. 5 is an end view of the same.

Fig. 6 is a fragmentary elevation on an enlarged scale showing the construction of the upper portion of the curtain and the method of securing the same to the rings.

Fig. 7 is a fragmentary perspective view showing how the brackets support the portière rods.

Fig. 8 is a fragmentary plan view of one of the brackets showing the method of forming the pins.

Fig. 9 is a fragmentary perspective view

showing the curled finger for holding the portière cord, and

Fig. 10 is an elevational view of the device employed in connection with a stage.

Referring more particularly to the drawings 11 indicates a window, door, stage, or other casing to which the improved hanger 60 is adapted to be secured.

Referring more particularly to Figs. 2 and 3 one of the brackets 12 is herein shown, the same having the outline illustrated or any other ornamental configuration. This 65 bracket is an angle bracket having an upper horizontally extending ledge 13 to which the curtain rod 14 is secured at one end in any suitable manner. A slot 15 is made in the vertical portion of the bracket 70 and preferably near the lower portion thereof to receive a nut, screw, or other fastening 16 by which the bracket 12 is secured to the side of the casing 11 and near the upper portion thereof as shown in Fig. 1. The slot 15 75 is elongated in a vertical direction to provide for the adjustment of the brackets 12 as to height.

The bracket 12 is also slotted and cut away as indicated at 17, the material there- 80 of being cut and punched out to form an upwardly curled finger 18 for a purpose to be later described. The underside of the ledge 13 carries a double sheave block 19 through which the cord 20 is trained.

The ledge 13 is also provided with a pair of upstanding pins 21 and 22 formed near the lateral edges thereof and preferably made from the sheet metal of which the bracket is formed.

These pins 21 and 22 are preferably formed in the manner shown in Figs. 7 and 8. In Fig. 8 the metal rectangular blank 23 is first cut out from the top portion of the ledge 13, leaving the narrow neck 24 to connect the blank 23 with said ledge.

The blank 23 is afterwards folded upwardly about this neck 24 until it assumes a position standing upwardly at right angles to the plane of the ledge 13 after which said 100 blank is rolled about in opposite directions to provide a tubular pin as indicated by dotted lines in Fig. 8.

Referring now more particularly to Figs. 4 and 5 a similar bracket 25 is herein shown 105 having a similar slot 26 through which the

fastening 27 is adapted to engage for adjustably holding the bracket 25 to the opposite side of the casing 11. This bracket is also similarly formed with a ledge 28 and 5 with pins 29 and 30 upstanding therefrom.

The ledge 28 also provides for receiving the other end of the curtain rod 14 which is attached thereto in any appropriate manner. The bracket 25 also carries a curled 10 finger 31 just beneath the ledge 28 which co-operates with the previously mentioned finger 18 on the bracket 12.

A single sheave block 32 is carried by the bracket 25 beneath the ledge, it being noted 15 that the sheave contained therein is mounted on a vertical axis, as compared with the horizontally mounted double sheave on the bracket 12. The sheave block 32 provides for receiving and forming a bight in the 20 end of the cord 20.

The curtain rod 14 carries curtain rings 33 for supporting a two-part curtain, the parts of which are numbered 34 and 35 respectively, the same being divided centrally 25 and adapted to slide together with the rings 33 back and forth on the rod 14 whereby to open and close the same.

Referring more particularly to Fig. 6 the 30 upper edge of the curtain sections are provided with tapes 36 which are sewed thereto at separated points by the lines of stitching 37 the portions between the stitching being looped away from the curtain to receive the cord 38 which is carried alternately through 35 the loops of the tape 36 and through the curtain rings 33. The ends 39 of the cord 38 are secured to the curled fingers 18 and 31 on the brackets.

The curtain operating cord 20 is formed 40 into two runs 40 and 41 for passing through the single sheave block 32 on the bracket 25 and one run thereof is knotted to the first ring of the curtain section 35 as indicated at 42. The run 41 of the curtain operating 45 cord is knotted as indicated at 43 to the first ring of the other curtain section 34. As indicated in Figs. 1 and 6 the two runs 40 and 41 of the curtain operating cord, after going through the double sheave 50 block 19, extend downwardly at the side of the casing 11 and are within convenient reach of an operator who may pull either the one run or the other according to the desire to open or close the curtain sections 55 34 and 35.

The curtain rod 14 is preferably telescoped for the purpose of adjusting the same as to length whereby the rod may be

shortened or lengthened to accommodate casings of different sizes.

Other hollow and telescoping rods 44 are also provided, one at each side of the curtain rod 14 and are adapted to hold portières 45 in such a way as to conceal the various brackets, rods, and the curtain opening and 60 closing appliances. The portières 45 are preferably draped in the manner shown in Fig. 10. The ends of the portière rods 44 are flattened as indicated at 46 in Fig. 7 and are provided with perforations 47 which 65 adapt them to fit over the upstanding pins on the bracket ledges.

In use the window or stage or other casing has the appearance illustrated in Fig. 10 when the improved curtains and portières 70 are hung therein. An operator standing at one side thereof may select either operating cord and may consequently move the runs 40 and 41 of the operating cord in a desired 75 direction to open and close the curtain sections, the cord running freely through the sheaves in a noiseless manner.

The portière rods 44 are easily lifted from the pins which provides for the interchange of the portières and their convenient re- 80 moval for the purposes of cleaning.

I desire it to be understood that I am not limited to the size, form, or proportion of the various parts, and various changes and modifications may be made provided the 90 same are within the spirit of the invention as defined by the appended claim.

What is claimed is:

A combined curtain and portière hanger comprising a pair of brackets adapted for 95 mounting upon the opposite sides of a casing, said brackets having sheaves therein and having transversely spaced apart upstanding fingers, a curtain rod adapted to be secured at opposite ends to said brackets 100 between the fingers thereof and arranged to receive a curtain, a cord trained over said sheaves and connected to said curtain for manipulating the same, and portière rods having apertured ends adapted to engage 105 over said fingers for supporting the portières at opposite sides of the curtain to conceal the upper and outer edges of the same.

In testimony whereof, I have affixed my 110 signature in presence of two witnesses.

EVELYN N. ELLIS.

Witnesses:

MRS. KENNETH BRYANT,
IDA M. LEVEL.
